US00D986635S

(12) **United States Design Patent** (10) Patent No.: **US D986,635 S**
(45) Date of Patent: **** May 23, 2023**

(54) **CUSHION**

- (71) Applicant: **Lijun Xia**, Guangdong (CN)
(72) Inventor: **Lijun Xia**, Guangdong (CN)
(**) Term: **15 Years**
(21) Appl. No.: **29/820,177**
(22) Filed: **Dec. 20, 2021**
(51) LOC (14) Cl. **06-09**
(52) U.S. Cl. **USPC D6/601**
(58) **Field of Classification Search**
USPC D6/595, 596, 604, 605, 606, 601
See application file for complete search history.
